UNITED STATES PATENT OFFICE.

AMBROSE A. OSBORN, OF SAN FRANCISCO, CALIFORNIA, ASSIGNOR TO CALIFORNIA CEREAL COMPANY, OF SAN FRANCISCO, CALIFORNIA, A CORPORATION OF CALIFORNIA.

MANUFACTURE OF STARCH.

SPECIFICATION forming part of Letters Patent No. 746,369, dated December 8, 1903.

Application filed September 10, 1903. Serial No. 172,546. (No specimens.)

To all whom it may concern:

Be it known that I, AMBROSE A. OSBORN, a citizen of the United States, residing in the city and county of San Francisco, State of California, have invented certain new and useful Improvements in the Manufacture of Starch; and I do hereby declare the following to be a full, clear, and exact description of the same.

10 My invention relates to the art of manufacturing starch mechanically; and it consists in the novel process and in several of the steps thereof, which I shall hereinafter fully describe.

15 The object of my process is generally to quicken the process and improve the output both in quantity and quality. These objects are attained at two well-defined steps in the process—namely, in the production of the starch-milk and its separation from the gluten and in the drying of the starch, whereby a starch more nearly anhydrous than is common is produced.

20 Referring to the accompanying drawings, which serve to illustrate my process, Figure 1 is an elevation of an assembled apparatus, portions of which are broken away to more clearly show the character of the several parts. Fig. 2 is a plan of same.

25 In thus illustrating an apparatus in which my process is carried out it must be understood that the assemblage of the several parts in the manner shown is merely for the purpose of illustration. These parts may be differently relatively located, and several minor connections may be employed and the power applied variously without affecting my process, which remains the same in its sequence of steps irrespective of the details of construction and arrangement of the apparatus. With this understanding I will first describe the apparatus shown in the drawings.

30 On the top floor A is a hopper B to receive the flour. From this hopper extends a screw conveyor C to an elevator D, the discharge-spout *d* of which is in communication with the dough-mixer E. This mixer may be of any well-known pattern. I have here indicated it as having a mixing-shaft *e* and an end discharge *e'*.

F is a water-tank indicating any suitable water-supply. A pipe *f* leads from this tank to the mixer, as shown. Under the discharge of the mixer is a bin G to receive the dough. Below this bin is the washer H. This washer 55 is in the shape of a rotating churn comprising a barrel *h*, mounted upon end gudgeons *h'* and having within it rolls *h*², to which individual axial motion is imparted through gears (indicated at *h*³) by the rotation of the 60 barrel on its own axis, all after the manner of rotary churning of this kind. The barrel has a door *h*⁵ and some plugged holes *h*⁶. One of the gudgeons *h'* is hollow, as shown in Fig. 1, and into it a branch *f*² from a pipe *f*³ from 65 tank F enters. From this gudgeon extends into the barrel a sprinkler-pipe *h*⁷. Below the washer is a chute I, leading to a bin J.

Passing to the next floor A' there are settlers K. These may be in any suitable number. I have here shown two, one of which is broken away to show a rotary stirrer *k* within, each settler being provided with stirrers. Water is supplied to the settlers by a pipe *f*⁴ from a branch *f*⁵ of pipe *f*³. Holes *k*' in the 70 lower portion of the settlers enable the lower contents to be drawn off. Below the settlers is a trough L, which leads to a hopper M, adapted to discharge into a centrifugal separator N, located in the basement A². This 75 separator may be of any usual type adapted for the purpose.

In the basement is located the drier O. This consists of a casing in which the trays P are mounted in tiers in such a manner as 85 to leave a zigzag passage for air, as is indicated in Fig. 1 by the arrows.

Q is a fan connected on its suction side by a pipe *q* with a cooler vessel R, having an air-inlet pipe *r*. In this vessel is located a cooling or refrigerator coil S. The discharge end of the fan Q communicates by a pipe *q'* with the base of the drier, and in said base is located a heater-pipe T.

U is a motor which, as indicated, drives by 95 a belt *u* a shaft V. From this shaft a belt *c* drives the screw conveyor C, belts *d'* drive the elevator D, a belt *e'* drives the mixer E, a belt *h*⁸ drives the washer H, gears *k'*, counter-shaft *h*², with clutches *k*⁴, and bevel-pin- 100

ions k^5 control and drive the stirrers k of the settlers K, and a belt n drives the separator N.

In this apparatus the process carried out is as follows: Flour in suitable quantities is fed to the hopper B and by the screw conveyer C is carried to the elevator D, by which it is raised to and delivered to the mixer E. Water from pipe f is also delivered to the mixer. In this mixer the water and flour are thoroughly commingled into a paste or dough, which is delivered from the discharge e' of the mixer to the bin G. At proper times this dough is placed by shoveling or otherwise into the barrel of the washer H through the door h^5 . When the barrel is charged, the door is closed and the barrel is rotated, and during rotation water is supplied to the barrel from the sprinkler-pipe h^7 , which sprays it upon the dough. The rolls h^2 in the barrel, rotating on their own axes, press the dough between them, and this action, together with the agitation of the rotation of the barrel and action of the sprinkling water, squeezes and washes out the starch, separating the dough into starch-milk and gluten. The churning and spraying action to which the dough is thus subjected is particularly efficient in bursting the walls of the vegetable-cells to liberate the starch granules and wash them out free of other associated cell contents. With cereals generally, and especially with wheat, where the gluten forms a large proportion, this comparatively severe churning or squeezing action is necessary, and by the constant spraying of the water the liberated starch granules are washed out of the cells and pass off in the milky mixture in suspension, leaving the gluten, an insignificant proportion only of which passes off with the starch. The starch-milk is discharged from the churn or washer H through the holes h^6 and over the chute I into the bin J. From this bin it is taken by any suitable means, as by channels or pumps (not shown) to the settlers K. When a charge is in the settlers and a proper time elapses to effect a settling of the heavier starch material to the bottom, the upper water is drawn off, and clear water is added from pipe f^4 , and the stirrers k are set in operation to stir up the mass thoroughly, after which a second settling is allowed to take place. Finally after a period of settling the upper water is drawn off and the thick starch material is discharged through the holes k' . The starch now passes through trough L to hopper M, and by the latter is delivered to the separator N. In the separator the starch is freed of its water, being thrown to the walls of the separator and plastered thereon. From this it is cut in cakes and placed in trays, which are then put into the drier O. In this drier it is subjected to the action of air, which air is first

cooled by the refrigerator-coil S and is then warmed by the heating-pipe T. This preliminary cooling of the air I have found of importance in that it appears to render said air more absorbent of moisture. In fact I have found that the cold air, even without a subsequent heating, acts efficiently but more slowly in taking the moisture from the starch; but with a subsequent heating the air acts rapidly in divesting the starch of its moisture. When the drying is complete, the starch is ready for the market, and in practice I have found that it is most effectually dehydrated, being a nearly anhydrous product, much to be desired.

Having thus described my invention, what I claim as new, and desire to secure by Letters Patent, is—

1. That step in the process of manufacturing starch which consists in squeezing the dough during revolving agitation and simultaneous water-spraying.

2. A process of manufacturing starch, which consists in mixing the flour with water to form a dough, subjecting the dough to a revolving agitation during water-spraying to separate the starch-milk from the gluten, settling the starch-milk, separating the starch, after settling, from the remaining water, and finally drying said starch.

3. A process of manufacturing starch, which consists in mixing the flour with water to form a dough, squeezing the dough during revolving agitation and simultaneous water-spraying to separate the starch-milk from the gluten, settling the starch-milk, separating the starch, after settling, from the remaining water, and finally drying said starch.

4. The process of manufacturing starch, which consists in mixing the flour with water to form a dough, squeezing the dough during revolving agitation and simultaneous water-spraying to separate the starch-milk from the gluten, settling the starch-milk, separating the starch, after settling, from the remaining water, and finally drying said starch by means of air which has been previously cooled.

5. The process of manufacturing starch, which consists in mixing the flour with water to form a dough, squeezing the dough during revolving agitation and simultaneous water-spraying, to separate the starch-milk from the gluten, settling the starch-milk, separating the starch, after settling, from the remaining water, and finally drying said starch by means of air first cooled and then heated, prior to its action on the starch.

In witness whereof I have hereunto set my hand.

AMBROSE A. OSBORN.
